REGISTERING MEANS FOR TAXIMETERS

Abraham Weiss, New York, N. Y., assignor to
Edward Weiss, New York, N. Y.

Application December 17, 1930, Serial No. 502,950

2 Claims. (Cl. 235—30)

The present invention relates to motor vehicles of the taxi type, the taximeter of which is controlled by a so called "flag". With such vehicles, the owner has to depend upon the honesty of the driver for the fare collected. Frequently unscrupulous drivers make special deals with the passengers and fail to throw the "flag" into registering position so that the fare collected is unrecorded and is a loss to the owner of the vehicle.

The object of this invention is to provide a device wherein the time or distance during which the driver carries a passenger without setting the "flag" to registering position is recorded.

This object I may accomplish by providing electro-magnetically operated registering means controlled automatically through an electric switch in the passenger compartment of the vehicle while the "flag" of the meter is in non-registering position.

With the above and other objects in view, my invention comprises the novel combination, arrangement and construction of elements herein-after to be more fully described, shown and defined in the appended claims.

In the accompanying drawing which forms part of this specification and in which similar reference characters denote corresponding parts:—

The figure is a diagrammatic view of my device.

My invention is embodied in a device which will register mileage only when the driver attempts to drive his vehicle with the "flag" in unregistering position while the vehicle is occupied by a passenger. Here, as before, *b* represents the taximeter of any well known type. *23* represents a rotatable shaft suitably journaled in a wall of the casing *21* and to the outer end of which may be attached the usual flexible transmission cord *24* which may be geared in usual manner by a gear *25* to one of the vehicle wheels, (not shown). The inner end of said shaft *23* has keyed thereto a gear

wardly therefrom are two pins *31* and *32*. Supported in suitable bearings in said casing is a shaft *33* whose lower end is provided with a cross arm *34* adapted to be engaged by said pins *31* and *32* and thereby couple said shaft to said disk *30*. Mounted on said shaft is a worm *35* which meshes with a worm gear *36* suitably fixed on a shaft *36a* supported in the casing *21*. A second gear *37* concentric with gear *36* which on shaft *36a* meshes with a gear *38* fixed on a rotatable shaft *39*.

Slidably keyed on said shaft *39* is a toothed element *40* of a sliding clutch. Rotatively mounted about said shaft is a gear *41* having fixed thereto the second toothed interlocking element *42* of the sliding clutch. Said gear *41* is geared to well known counting or registering mechanism *43* used in the present instant to register miles in steps of tenths, a column wheel *43a* registering tenths of miles, a second *43b* registering units and a third *43c* recording tens. The construction of this unit is well known and requires no detailed description thereof. It is sufficient to say that the gearing therein is such that for each complete rotation of the tenths column wheel, the units column wheel rotates a tenth of a revolution and likewise for each complete rotation of the units column wheel the tens column wheel rotates a tenth of a revolution. Other suitable mileage registers may be used. The gearing ratio from the vehicle wheel through to said tenths unit wheel of course must be such that said tenths wheel will rotate a tenth of a revolution for each $\frac{1}{10}$ of a mile covered by the vehicle.

It is of course, understood that the above described registering mechanism is auxiliary to the regular taximeter registering mechanism, which latter does not form part of the present invention and is not shown in detail to secure clarity of the drawing. Said taximeter mechanism however, is of course, in actual practice in the casing *21* and controlled in well known manner by the flag *a*.

In order to slide the clutch element *40* into engagement with the corresponding element *42* on gear *41*, I provide the lever *44*, pivoted intermediate its ends. The lower arm *44'* of said lever engages an annular recess in said element *40*. Suitable resilient means *46* attached to the upper arm *44²* of lever *44* tends to swing said arm so as to keep member *40* out of engagement with the member *42* i. e. to keep the clutch open.

The lever *44* is adapted to be actuated only when the flag *a* of the taximeter is up and a

passenger occupies the vehicle. To this end a solenoid coil 47 is provided. The front end of the core 48 of said solenoid is pivoted in a slot 44³ in the upper arm 44² of lever 44. 11 denotes the switch controlled from the "flag" a of taximeter b which may be of the conventional construction. One of the contact pieces of the switch 11 is connected by wire 12 to one of the contact pieces of the switch 10, the second contact piece of the latter being grounded as at 16³. 13 denotes a source of electrical energy, such as a battery, one pole of which through a wire 13' is connected to the second contact piece of switch 11. The second pole of the said source 15 of electrical energy is connected by wire 13² to one terminal of the solenoid 47, the second terminal of the latter being connected by wire 14³ to one terminal of a switch 22² adapted to be operated from the accelerator pedal c of the vehicle, the other terminal of said switch being connected by wire 14⁴ to the ground. 20

The operation of my device is as follows:—

If the flag is up and no one is in the back compartment the circuit is open through switch 10 and hence the core 48 of the solenoid 47 is unactuated, and non-paying miles are not registered, the sliding clutch members 40 and 42 being disengaged. As a passenger enters or seats himself in the rear compartment switch 10 is closed. If the driver now attempts to drive the car with the "flag" up by pressing on the accelerator c, switch 22² is closed and the solenoid 47 is actuated, so that the non-paying mileage is registered. But as soon as the "flag" is lowered 35 the circuit through switch 11 is broken and no registering on the auxiliary register shown occurs.

It is obvious that the application of my invention is not limited to the details shown and described, and I do not wish to be limited thereby.

What I claim is:

1. In a motor vehicle having a passenger compartment, an accelerator pedal, a flag controlled taximeter, a source of electric power whose circuit includes a switch operated by the flag of

said taximeter and adapted to be closed when said flag is in nonregistering position, a second switch adapted to be closed when said passenger compartment is occupied, and a third switch adapted to be closed by the depression of said accelerator pedal, mileage registering means adapted to be operated from a rotatable part of said vehicle, a clutch mechanism for controlling the operation of said registering means, composed of a pair of toothed elements, one of said elements being slidable relative to the other, the second of said toothed elements being geared to said registering means, a rock lever coupled to said slidable toothed element and electro-magnetic means controlled from said electric source and adapted to be energized when said first two named switches are closed, the solenoid of said electro-magnet being adapted to actuate said rock lever so as to engage said toothed elements with one another to render said registering means operative. 10 15 20

2. In a motor vehicle having a passenger compartment, an accelerator pedal, a flag controlled taximeter, a source of electric power whose circuit includes a switch operated by the flag of 25 said taximeter and adapted to be closed when said flag is in non-registering position, a second switch adapted to be closed when said passenger compartment is occupied and a third switch adapted to be closed by the depression of said accelerator pedal, mileage registering means adapted to be operated from a rotatable part of 30 said vehicle, means for controlling the operation of said registering means including two elements displaceable relative to one another and of which 35 one is operatively connected to said registering means, rocking means coupled to the other of said elements and electro-magnetic means controlled from said electric source and adapted to be energized when said first two named switches 40 are closed and to actuate said rocking element so as to engage said two elements with one another to render said registering means operative.

ABRAHAM WEISS. 45
